Primary Examiner — Tamara L Hahn(74) Attorney, Agent, or Firm — Polson Intellectual Property Law, PC; Margaret Polson(57) CLAIM

The ornamental design for a handle tray for a cart as shown and described.

DESCRIPTION

FIG. 1 is a perspective of the handle tray for a cart.

FIG. 2 is a right side view thereof.

FIG. 3 is a left side view thereof.

FIG. 4 is a back side view thereof.

FIG. 5 is a front side view thereof.

FIG. 6 is a bottom side view thereof; and,

FIG. 7 is a top side view thereof.

Contour is shown with grey scale shading, no difference in color, texture or material is claimed. The features shown in light grey in the drawings depict portions of the handle tray for a cart and form no part of the claimed design.

1 Claim, 7 Drawing Sheets(56)
